F. T. WARNER

PENHOLDER

Filed August 19, 1925

WITNESS:

J. L. Wright

BY *Victor J. Evans*

ATTORNEY

UNITED STATES PATENT OFFICE.

FRANKLIN T. WARNER, OF HOMER, NEW YORK.

PENHOLDER.

Application filed August 19, 1925. Serial No. 51,225.

This invention relates to stationery, particularly to penholders, and has for its object the provision of a novel device for holding a pen point, the holder including clamping means for positively gripping the pen, the clamping means being equipped with operating means whereby to effect release of the holding action on the pen so that changing thereof will be facilitated.

10 An important object is the provision of a device of this character which will be simple and inexpensive in manufacture, easy to use, positive in action, efficient and durable in service, and a general improvement in the art.

With the above and other objects and advantages in view, the invention consists in the details of construction and the arrangement and combination of parts, to be hereinafter more fully described and claimed, and illustrated in the accompanying drawings, in which:

Figure 1 is a perspective view of the penholder with a pen point held therein.

25 Figure 2 is a fragmentary front elevation.

Figure 3 is a vertical section taken on the line 3—3 of Figure 2.

Figure 4 is a detail section taken on the 30 line 4—4 of Figure 3.

Figure 5 is a perspective view of the clamping member, and

Figure 6 is a perspective view of the spring.

35 Referring more particularly to the drawings, I have shown the device as comprising a suitable elongated handle 10 of any desired or preferred material upon one end of which is secured a ferrule 11 formed preferably of sheet metal and necessarily of tubular form. At one side this ferrule is cut away along an incline as indicated at 12 and at an opposite point it is formed with a preferably circular hole 13 for a purpose to be described.

40 Mounted within the ferrule is a clamping member designated broadly by the numeral 14, which clamping member is substantially semi-cylindrical in form and constructed of suitable sheet metal. The cross sectional configuration of this clamping member is such that it will lie conformingly against the inner wall of the ferrule at that portion thereof provided with the hole 13. At one 45 end the clamping member 14 is preferably

somewhat cut away as indicated at 15 corresponding to the cutting away of the ferrule at the lines 12. Secured upon the intermediate portion of this clamping member is a plunger or button 16 which projects slidably through the hole 13 in the ferrule and which not only serves to retain the clamping member in position but also acts as means whereby the clamping member may be released to permit the pen point, indicated at 17, to drop out of the holder as will be explained.

Coacting with the clamping member is a substantially V-shaped spring 18 which may be formed as a single length of resilient wire 70 having a bend 19 therein, the bend being located in a slot 20 in the end of the handle 10 with the short arm of the spring bearing against the inner wall of the ferrule and its long arm bearing against the 75 end portion 15 of the clamping member 14.

In the use of the device, it will be seen that in order to insert a pen point 17 in the holder it is necessary that the operator press upon the button 16 to move the clamping member 14 away from the adjacent portion of the inner periphery of the ferrule so that the pen point may be inserted between the ferrule and the clamping member until the end thereof engages against the button, as 80 clearly indicated in Figure 3. The operator then releases the pressure upon the button and the spring 18 acts to force the clamping member into engagement with the pen point for holding it in place. Whenever it is desired to change the pen point it is merely necessary that the same operation be gone through with, the application of 85 pressure to the button releasing the pen so that it may drop out without it being necessary for the user to touch it with his fingers.

90 From the foregoing description and a study of the drawing, it is quite clear that I have provided a very simple, neat, attractive and convenient device for the purpose specified. It is believed that the construction, 95 operation and advantages will be readily apparent to one skilled in the art without further explanation.

100 While I have shown and described the preferred embodiment of the invention, it should be understood that I reserve the right to make such changes in the form, construction and arrangement of parts as will not depart from the spirit of the in- 110

vention or the scope of the subjoined claim. the ferrule engaging the clamping member, Having thus described the invention, I the spring means being formed as a single length of resilient wire bent into substantial claim:—

In a penholder, a handle, a ferrule member secured upon one end thereof and formed with a hole, a clamping member disposed within the ferrule and having a button projecting through said hole, and serving as a pivotal mounting, the clamping member cooperating with the adjacent portion of the ferrule for maintaining a pen in position, and spring means within

the ferrule, the spring means being formed as a single length of resilient wire bent into substantial V-shape, one end portion engaging against the inner periphery of the ferrule and the other end portion engaging against the inner side of the clamping member, the end of the handle being formed with a slot receiving the bent portion of the spring.

FRANKLIN T. WARNER.
